PRINTING PRESS

Levi P. Hughes, Summit, N. J.

Application February 6, 1936, Serial No. 62,578

6 Claims. (Cl. 101—316)

The invention relates to printing presses, and more particularly to special presses for printing special matter on multiform sheets.

According to the invention, a machine of the above type is provided in which suitable adjustments are made to accommodate different size forms; different numbers of forms per sheet and different arrangements of the printed matter on the forms.

10 A further feature of the invention is the provision of pincer-like gripping devices for slidably engaging the edges of the sheets in such manner as to maintain the sheets in contact with a longitudinal guide through the machine.

15 A still further feature of the invention is the provision of a special movement for the printing head in which the printing head is given both a vertical and rotative movement. This movement is such that when the printing head is in its upper position, the type faces the front of the machine so that the operator can inspect it and when the printing head is in its lower position, the type faces downwardly to print upon the sheet resting on the platen.

20 25 Other objects of the invention include the provision of a relatively simple, dependable, highly efficient and convenient apparatus of the type above indicated.

30 Although the novel features which are believed to be characteristic of this invention will be particularly pointed out in the claims appended hereto, the invention itself, as to its objects and advantages, and the manner in which it may be carried out, may be better understood by referring to the following description taken in connection with the accompanying drawings forming a part thereof, in which

Fig. 1 illustrates a side view of the machine;

35 Fig. 2 is a longitudinal section through the machine;

Figs. 3 and 3a are supplementary sections taken on the line 3—3 of Fig. 2, these figures being coextensive along the lines A—A;

40 Fig. 4 is a vertical transverse section taken on the line 4—4 of Fig. 2;

Figs. 5 and 6 are transverse sections taken on the lines 5—5 and 6—6 of Fig. 2;

45 Fig. 7 is a detailed side view showing the mounting of the printing mechanism facing the left side of the machine;

50 Fig. 8 is a view similar to Fig. 7 facing the right side of the machine;

55 Fig. 9 is a longitudinal section taken through the printing mechanism;

Fig. 10 is a transverse section taken on the line 10—10 of Fig. 7;

5 Fig. 11 is a perspective illustrating the construction of the stop mechanism and particularly that of the first stop device;

Figs. 12 and 13 are side and end views respectively of a stop operating cam;

10 Fig. 14 is a perspective illustrating the construction and adjustment of one of the posterior stop mechanisms;

Fig. 15 illustrates one type of multiform sheet which may be printed by this machine.

15 In the following description and in the claims, various details will be identified by specific names for convenience, but they are intended to be as generic in their application as the art will permit.

Like reference characters denote like parts in the several figures of the drawings.

20 In the drawings accompanying and forming part of this specification, certain specific disclosure of the invention is made for purposes of explanation, but it will be understood that the details may be modified in various respects without departure from the broad aspect of the invention.

25 Referring to the drawings, and more particularly to Figs. 1, 2, 3 and 3a, the general arrangement of the machine includes a frame 20; a feed board 21 for supporting the sheets to be printed; a feed roll 27 for picking up the sheet 30 and feeding it into the machine when released by gate 28; platen 22 between which and printing head 26 the sheet is printed; traveling belts 23 for carrying the sheet through the machine; adjustable stops 33, 32, 31, 30 and 29 for successively stopping the sheet with the forms in proper position for printing; slidable friction pincers 34, 35 and 36 for maintaining the sheet against guide bar 37 during the printing operations and fly sticks 38 for transferring the sheets onto a 40 delivery plate 25.

45 Although the machine may be used for printing many different kinds of multiform sheets, a sheet of bank checks is taken for purposes of explaining the invention. These sheets commonly run three or five checks to a sheet. The present machine is arranged to accommodate five checks per sheet or any lesser number of checks per sheet.

50 Referring to Fig. 15, a five bank check sheet is shown. These sheets are usually completely printed with everything except certain special printing, as for example, the check numbers and the name of the drawer, before coming to the present machine.

Referring to Fig. 15, the separate bank checks making up the sheet are denoted by 41. These checks are separated from each other and from the marginal stub 42 by perforated lines indicated by 43.

The machine according to the invention supplies the special data, such as check numbers, indicated by 44, and the printed name of the drawer, indicated by 45 and 46. The printed name may be placed near the signature, as at 45 and at the left hand side of the check, as at 46, or at any other position. The printed numbers may be placed at the left hand upper corner of the check, as at 44, or at any other corner of the check, the corresponding number being also printed on the stub. The name of the drawer will, of course, be the same on each check, but the check numbers will be consecutive.

Referring again to Figs. 1, 2, 3, 3a, 4, 5 and 6, the frame 20 comprises main side members 47 and 48 connected by cross members 49 and 50, bed 51 and other bars and tie rods to impart the necessary strength to the machine. The frame also includes the printing mechanism posts 52 and 53 (Fig. 4) which posts may be integral with the side members 47 and 48 or separate. If separate, these posts will be suitably bolted to the side members as will be understood by those skilled in the art. The frame supports the various mechanisms which will be described in detail hereinafter and also may support a suitable electric drive motor (not shown).

Printing mechanism

Referring now more particularly to Figs. 1, 2, 4 and 7 to 10, the printing head 26 is arranged to reciprocate vertically between the frame posts 52 and 53 and at the same time to have a rotative movement. When the printing head 26 is in its upper position, as shown in Fig. 2, the type faces the operator and when the printing head 26 is in its lower position, the type rests on the printed sheet, held between the type face and the platen 22.

The printing head 26 comprises an impression bar 54 supporting a chase 55. Chase 55 is a frame-like structure having type spaces 56, 57. In the spaces may be located the numbering mechanism for placing the consecutive numbers on the bank checks and also the type for printing the name of the drawer on the checks. If desired, the numbering mechanism may constitute an automatic numbering machine which automatically changes to the next higher number each time a number is printed.

Referring to Figs. 2, 4 and 10, the chase 55 is secured to impression bar 54 by chase retaining fingers 58 engaging in an angular seat in the top of the chase 55, the bottom of the chase also having an angular seat resting on bar 60. Suitable spring devices 59 yieldably hold the fingers 58 against the chase 55.

Suitable mechanism is also provided for lifting the fingers 58 to remove the chase. This mechanism comprises cam bar 61 having cam surfaces engaging the fingers 58. To remove the chase, a rod (not shown) is engaged against projection 61', and, with lug 361 acting as a fulcrum, the cam bar 61 is moved laterally to raise fingers 58, thus releasing the chase, as will be understood by those skilled in the art.

Referring to Figs. 2, 4, 7, 8, 9 and 10, the impression bar 54 is mounted to give the peculiar combined vertical and rotative movement above described. The impression bar 54 has a pair of

journals 66, 67 disposed in vertical sliding blocks 64, 65 which slide respectively in vertical ways 68, 69 in vertical posts 52, 53. Disposed within post 52 is chase turning block 70, this block having a cam roller 71 (Fig. 7) operating in cam slot 72 in cam plate 73 suitably bolted to post 52.

On the other side of the chase block or impression bar 54 is a chase aligning block 76 (Fig. 8) sliding within the post 53 and adapted to engage between aligning guides 77, 78. These aligning guides 77, 78 cooperate with machined surfaces 80, 81 on chase aligning block 76. This construction insures that the face of the type seats squarely on the platen 22. Adjusting slots 82 are provided and, if desired, adjusting bolts 83 may be provided to adjust the aligning guides 77 and 78 to give the desired setting.

To limit the lower movement of the impression bar, stop plates 84, 85 (Figs. 7, 8 and 10) are provided. These stop plates are located on opposite sides of the machine and within the posts 52, 53. For closing the space in which the chase aligning block 76 moves, a plate 79 may be secured to the post 53 (Fig. 8).

The impression bar is driven by a main cross head 88 (Fig. 4) to which it is connected by heavy rods 96, 97 passing through openings in bed 51. These rods 96, 97 are securely bolted to cross head 88 at one end and at the other end are provided with eyes 98, 99 journalled on the impression bar or chase block 54.

The main cross head 88 is driven by eccentrics 89, 90 mounted on eccentric sheaves secured to one revolution clutch shaft 91 (Fig. 4). The eccentrics 89, 90 are pivoted to cross head 88 by pivots 62.

The operation of one revolution clutch shaft 91 will be described later more in detail. It suffices to point out here that every time this shaft makes one revolution, the printing head 26 travels to its uppermost position, as shown in Fig. 2, at which point the chase 55 faces the operator. As the eccentrics 89, 90 pull the rods 96, 97 downwardly, the printing head 26 is guided downwardly by the vertical guideways 68, 69. This causes the cam roller 71 to ride in cam slot 72, causing the printing head 26 to rotate as it moves downwardly so that when it reaches its printing position, the chase 55 squarely faces the platen 22.

Inking mechanism

The ink cylinders are denoted in general by 101 (Fig. 4). They may be mounted on a shaft 102 journalled in the frame members 52, 53 and driven by a chain 103. Spreading rolls, indicated in general by 104, and mounted on shafts 110, 111 (Fig. 7) are provided for spreading the ink uniformly on the ink cylinders 101. The spreading rolls 104 are given a rotating movement by contact with the ink rolls 101 and at the same time they are given an axial movement by cam motion.

Referring to Figs. 4, 7 and 10, the shaft 102 carries a cam 106 which cooperates with followers 107, 108 (Fig. 7). These followers are pivoted on a shaft 109 suitably secured on the adjoining frame and carry projections 100 operating in grooves on pulleys 99 mounted on the shafts 110 and 111.

For transferring ink from the ink cylinders 101 to the type, transfer rolls, indicated in general by 112, 113, are provided. Referring to Figs. 2, 4 and 9, these rolls are mounted on shafts 114 and 115, these shafts being mounted in separate frames 116, 117. These frames 116, 117 are sepa-

rately pivoted at 122 to long side bars 120, 121 running in vertical grooves and operated by a special cam 123 on the one revolution shaft 91 (Fig. 4). Separate springs 124, 125 separately 5 and yieldably urge the rollers 112, 113 against the type face and ink cylinders 101.

For the purpose of transferring rolls 112, 113 back and forth between ink rolls 101 and the type face, special transfer mechanism is provided. Shafts 114, 115 have wheels or rollers 118, 119 riding on side rails 129, 130 mounted on the chase block 54 and on side bars 131, 132. These side bars are mounted on shaft 133 and are operated by a cam action. This cam action is caused 10 by rollers 134, 135 mounted on the bars 131, 132, which rollers ride in cam openings 136 (Fig. 9) in cam plates 137, 138 attached to the eyes 98, 99 of eye bolts 96, 97 (Fig. 9).

The long side bars 120, 121 (Fig. 4) are operated by a cross rod 126 pivoted to link 127 which in turn is pivoted to arm 128 (Fig. 1) pivoted to the frame. Lever 128 carries a follower working 15 on cam 123 which is mounted on one revolution shaft 91.

It will be noted that arms or tracks 129, 130 and 131, 132 overlap to provide a smooth path 20 for the wheels 118, 119 to permit smooth transfer of the ink carried by transfer rolls 112, 113 from inking rolls 101 to the face of the type.

As the impression bar 54 moves downwardly, the cam 123 is so arranged that the transfer rolls 112, 113 move upwardly. Thus while the impression bar or chase block 54 is engaging the platen 22, the transfer rolls 112, 113 are engaging 25 the ink rolls 101. As the chase block 54 moves upwardly and the chase 55 rotates to a position facing the operator, shown in Fig. 2, the transfer rolls 112, 113 roll to their lowermost 30 position to spread ink on the facing of the type. The separate supports for the rollers 112, 113 insure better contact between the transfer rolls and the ink rolls and type.

Gate

Referring more particularly to Figs. 2, 3 and 4, the gate 28 passes through an opening in the feed plate 190 to hold back the sheet until the printing mechanism is ready to receive it and to print the first form on the sheet. The gate operating mechanism is controlled from the longitudinal cam shaft 140 journaled in cross member 50 and in bed 51 (Fig. 2). Cam shaft 140 has a cam 141 (Fig. 4) cooperating with follower 142 on lever 143 fulcrumed at 144. Lever 143 is pivoted to link 145, which in turn is pivoted to lever 146 on shaft 147. Shaft 147 is suitably journaled in the frame of the machine and carries the gate fingers 28.

First stop mechanism

Referring now to Figs. 2, 5 and 11, the first stop mechanism includes stop fingers 33 directly behind the bed 51. The position of these fingers 33 is longitudinally adjustable for different jobs by means of adjusting nuts 157 located at the front side of the bed 51.

The stop fingers 33 are secured to cross plate 148 (Fig. 11) mounted on rods 149 pivoted at 70 150 to studs secured to fixed frame bar 151. The cross plate 148 reciprocates vertically with respect to adjustable cross bar 152, which bar has slots 153 for rods 149. Plate 148 has slots 154 through which pass headed screws 155. Cross 75 plates 148 may oscillate vertically between headed

screws 155 and strips 152' secured to the adjacent cross bar 152.

For adjusting the stop fingers 33 longitudinally of the machine, adjustable cross bar 152 and plate 148 are slidable on rods 149. An adjusting rod 156 is pinned to bar 152 and passes through fixed bar 151 to which it is held in adjustable relation by thumb nuts 157. To maintain the alignment of bar 152, nipples 158 are secured thereto and have telescopic relation with rods 159 secured to 10 fixed bar 151.

For driving the stop fingers 33 to raise them so as to stop the sheets to be printed, a cam assembly 161 on cam shaft 140 drives follower 162 on cross bar 163 normally resting on bed bars 178. 15 Rods 164 are pinned to cross bar 163 and pass through bed bars 178 through eyes 165 on rods 169. Springs 166 are interposed between heads on rods 164 and the eyes 165 and cotter pins 165' limit the upward position of eyes 165 on rods 164. 20

In operation, the fingers 33 are normally down out of the way. As the cam 161 rotates and engages follower 162, it raises rods 164 which in turn raise plate 148 carrying fingers 33. This places the fingers 33 in the path of the advancing 25 sheets, intercepting them so that one of the forms thereon may be printed. After the printing operation, the cam 161 permits the fingers 33 to drop out of the way, thus permitting the sheet to advance to the next stop position. 30

Additional stop mechanisms

Referring now more particularly to Figs. 2, 3, 3a, 11 and 14, additional sets of fingers 29, 30, 31 and 32 are provided for stopping the sheets at 35 subsequent positions to print the subsequent forms thereon. These sets of fingers are mounted on cross bars 167, 168, 169, 170 also resting on bed bars 178. Each of these finger supporting bars forms part of a frame including side members and an end member, each one of which is 40 adjustably mounted on a central longitudinal adjusting screw 175.

Since these frames and their adjustments are similar, it is only necessary to describe one in detail. Referring to Fig. 14, the frame is shown, of which cross bars 167 form a part. The side members 171 are secured to cross bar 167 and are also secured to blocks 172. These blocks 172 have projecting threaded screws 173 threaded in 50 openings in adjustable bar 174. Central adjusting screw 175 passes through adjustable bar 174 and thumb nuts 176 are provided for adjusting the bar 174 to the desired position.

Thus it will be seen that the position of stop 55 fingers 29 is determined by adjusting thumb nuts 176. The transfer bar 167 normally rests on bed bar 178, but when its particular cam 180 engages follower 187, the fingers 29 rise up to intercept the movement of the sheets. As the fingers 29 60 move up and down, the screws 173 in their recesses in adjustable bar 174 act as pivots.

It will be noted that one end of the long adjusting screw 175 rests in post 177 secured to frame cross member 49. The other end of this 65 adjusting screw is engaged in cross member 50 (Fig. 2). It will be furthermore observed, particularly from Figs. 2, 3a and 11, that the longitudinal frame members of each anterior stop mechanism lies inside the corresponding frame 70 members of the stop mechanism next posterior thereto and that the position of each set of stop fingers is adjustable by adjusting its corresponding thumb nuts on the main adjusting screw 175.

It will be noted that the bed bars 178 are sup- 75

ported by support members 180 (Figs. 2, 5 and 14) depending from guide bars 302 and by support members 180 (Fig. 11) to adjoining parts of the frame of the machine under the path of travel of the sheets.

5 *Cam construction*

Referring more particularly to Figs. 12 and 13, cam 161 for operating the first set of stop fingers will be described. This cam comprises a disc 162 axially adjustable on the cam shaft 140. This disc carries cam segments 181 and 182. Cams 183 and 184 are similar in construction to cam 161. Cams 185 and 186, however, have only a single cam segment. All cams, however, are axially adjustable on shaft 140 to correspond with the longitudinal adjustment of their corresponding stop fingers and to permit the desired cam segment to engage its follower.

Two segment cams 161, 183 and 184 are for 20 use with sheets carrying either three or five forms and cams 185 and 186 are only used with sheets carrying five forms. Thus, for a three form sheet, only cams 161, 183 and 184 are used. In this instance, cams 185 and 186 are adjusted so 25 as to have no operation on their followers. For three form sheets, the cams are adjusted so that their longer segments engage their followers. For five form sheets all of the cams are used and the three two-segment cams are arranged so 30 that their shorter segments engage their followers.

Sliding pincers

Referring to Figs. 3, 4 and 5, frictional grippers or pincers 34, 35 and 36 are provided for frictionally grasping the sheets and holding them against the lateral guide 37. Each of these pincers has two movements, namely, the opening and closing of the jaws and the lateral movement of the pincers as a whole. As shown particularly in Fig. 3, these pincers operate through openings in the guide 37. The guide is undercut at 189 (Fig. 10) and is secured to the bed 51 and to the frame of the machine in the manner indicated. As shown in Fig. 4, a stationary plate 190 registers with the bottom of the groove 189 and, as shown in Fig. 10, the platen 22 registers with the groove 189.

As these pincers are substantially identical, a 50 description of one will suffice for all.

The pincers 36 comprise a lower jaw 195 and an upper jaw 196. The lower jaw 195 is fixed to the lever 193 and is disposed below the supporting surface for the sheets so that it will 55 easily pass under the sheets. The movable upper jaw 196 is pivoted to the lever 193 at 197 and a spring 198 operates to yieldably keep the pincers closed.

Lateral movement of the pincers is caused by a 60 cam 192 (Fig. 4) on cross head 88 operating a follower 211 on lever 212 secured to shaft 194 journalled in the bed 51. Secured to shaft 194 are the several levers, one of which is denoted by 65 193 for supporting the pincers 34, 35 and 36. As the cross head 88 moves up and down, the cam 192 will cause the pincers to move in and out laterally.

The opening and closing of the pincer jaws is 70 caused by control shaft 199 (Fig. 4) mounted on the frame of the machine. Shaft 199 supports a series of arms, one of which is denoted by 75 200 (Fig. 3) and carrying a roller 201 which engages the upper jaw 196 to open the jaws as they move toward the sheets and to close the jaws as they move away from the sheets.

Shaft 199 is operated by arm 202 (Fig. 3), which in turn is controlled by rod 203 (Fig. 4). Rod 203 is pivoted to lever 204 which carries follower 205 operated by cam 206 on the one revolution shaft 91.

5

Delivery

Referring more particularly to Figs. 1, 2 and 3a, the fly sticks 38 are mounted on fly shaft 262. These fly sticks carry stops 309 and fit in recesses 10 in the frame in such way as to receive the sheets carried by the belts 23. The fly shaft 262 carries a pinion engaged by a rack 263 slidably in a holder 269. The rack 263 is operated by shaft 264 having a fork 265 receiving shaft 260. Shaft 260 carries cam 266 which engages a follower 267 on 15 fork 265 causing rod 264 to oscillate against the tension of spring 268. As the rod 264 oscillates back and forth, the fly sticks 38 execute an approximately 180° movement, flipping the 20 sheets received thereon while in the position shown in Fig. 3a and delivering these sheets onto the delivery plate 25 (Fig. 1).

Path of sheets through machine

For feeding the sheets to the printing position, 25 a feed roller 27 (Fig. 2) mounted on shaft 255 is provided. This feed roller operates through an opening in feed plate 190 and has cooperating therewith a series of balls 207 held in suitable holders (Fig. 3) supported by cross bar 303. 30 Hold-down fingers 304 are also provided. This feed roller suffices to feed the sheets across the platen 22 where they are engaged successively by the stops 33, 32, 31, 30 and 29.

From the platen 22 the sheets are carried by 35 a series of moving belts 23 resting on bed plates 210 (Figs. 5 and 6). These belts are supported by pulleys 213, 214 and 215 (Fig. 2). A series of angular members 216 are provided for transferring the sheets from the platen 22 to the 40 belts 23.

For holding down the sheets against the belts 23, a series of balls 208 located in holders 209 are provided. These holders are supported by bar 209'. The several stop fingers 29, 30, 31 and 45 32 project up between the belts 23 in stripper channels 301 suitably supported by bar 209'. The stop fingers pass through slots in guide bars 302 (Figs. 3, 3a, 5 and 6).

It will be noted that the bed plates 210 and 50 guide bars 302 are supported, at their back ends, on frame cross bar 50 (Fig. 6) and at their front ends on cross bar 306 (Fig. 5) resting on bed bars 178 which in turn are supported by rods 180' extending to the side members of the frame 55 of the machine.

Driving mechanism

Referring more particularly to Figs. 1, 2, 3, 3a and 4, the main drive shaft 250 has a fly 60 wheel thereon driven by a belt 217, which in turn is driven by a suitable motor either located on the machine or on a separate support. Drive shaft 250 rotates at all times and drives belt shaft 253 by chain 254. Belt shaft 253 in turn 65 drives ink cylinder shaft 102 by chain 103. Shaft 215', on which pulley 215 is mounted, drives feed roller shaft 255 by chain 218. These shafts do not require any timing and hence can run continuously. All other shafts are under the control of one revolution shaft 91.

Main drive shaft 250 supports a hub on which gear 251 is frictionally mounted. Gear 251 drives gear 252 mounted on one revolution shaft 91. Gear 252 runs loosely on one revolution shaft 91, 75

but may be connected thereto by a one revolution clutch 93 (Fig. 4). One revolution clutches are well known and, as such, form no part of the present invention. The frictional engagement between the hub on main drive shaft 250 and gear 251 is necessary to take up the shock which would otherwise occur when the one revolution clutch 93 is suddenly engaged.

The one revolution clutch is controlled by foot pedal 94 (Fig. 1) which is suitably pivoted to the frame and which operates a link 95 which operates one revolution clutch 93. The one revolution clutch operates in such manner that when pedal 94 is depressed and immediately released the one revolution shaft 91 makes one complete revolution and stops.

One revolution shaft 91 drives sprocket 219 by chain 257. Gear 319 carried on the rear of sprocket 219 drives gear 256 mounted on shaft 258. Gear 256 is a change speed gear and is replaced according to the number of forms per sheet. Gear 319 is journaled on bar 220 which is adjustable between positions denoted by 221 for different size gears. Shaft 258 drives main cam shaft 140 through bevel gears 259 (Fig. 2).

Fly stick operating shaft 260 is driven by chain 261 from shaft 258.

Operation

To operate the machine, it is first determined the number of forms per sheet and the size of the forms. The chase 55 is supplied with the desired type and the stops are adjusted to register each form on the sheet directly under the printing head. The several cams 161, 183—186 are adjusted to give the desired timing action.

The sheets to be printed are fed by an operator, one by one, onto feed plate 190. These sheets are picked up by feed roller 27 and carried to gate 28. When the operator depresses foot pedal 94, gate 28 rises at the proper time and the sheets are fed to the first position against stop fingers 33. The printing head comes down and prints the first form. As the printing head rises, stop fingers 33 drop and the sheet moves against the next stop fingers 32 at which position the second form is printed. As the printing head again rises, the sheet advances until it engages the stop fingers 31 at which position the third form is printed and so on until all the forms are printed and the belts 23 carry the sheets to the delivery mechanism. The periodic operation of the fly sticks 38 in timed relation to the rest of the machine carries each sheet off the rollers and delivers it onto the delivery plate 25.

All the while the sheets are being fed through the machine, the sliding pincers 34, 35 and 36 slidably pull the sheets against the guide bar 37, holding the sheets always in proper register during the printing operation. It should here be noted that the pincers are so arranged that at no time is any sheet gripped at one end only during the printing operation. If the sheet is gripped at the ends, it is always gripped by two or more pincers. If it is gripped by a single pincer, it is gripped at the middle of the sheet. This distribution of pincers prevents any misalignment of the sheets during the printing operation.

The machine is adjustable to any number of forms per sheet and to any size form or sheet within the limits of the machine. The positions of the various stop fingers are adjustable. The positions of the cams are adjustable to corre-

spond to the stop fingers and also to correspond to the number of forms per sheet. Furthermore, the timing of the cam shaft is also adjustable by the change speed gears 319, 256.

The combined vertical and rotative movement applied to the printing head 26 is of advantage in that it facilitates inking the face of the type and it exposes the type form to the operator when in its upper position. Thus, the operator can set or change numbers of the consecutive numbering machine, if necessary, to correct the numbering. The operator can also note the condition of the type and, if necessary, take suitable action to remedy any defects. When the type head assumes its printing position, provision is made for it to be absolutely true so as to make a perfect printed form.

While certain novel features of the invention have been disclosed and are pointed out in the annexed claims, it will be understood that various omissions, substitutions and changes may be made by those skilled in the art without departing from the spirit of the invention.

What is claimed is:

1. In a printing press, a horizontal platen, means for feeding the sheets to be printed across the top of said platen from the front of the machine, an impression bar, printing devices secured to said impression bar, operating devices secured to said platen, said operating devices acting upon said impression bar to cause it to contact said sheets horizontally on said platen and to cause said impression bar to rotate upwardly and vertically away from said platen so that its printing face is visible to the operator at the front of the machine, each time it moves upwardly.

2. In a printing press, a platen, impression bar mechanism comprising first and second standards having vertical guideways, said standards projecting upwardly from said platen, sliding blocks in said guideways, a chase block journaled in said sliding blocks, a chase turning block connected to said chase block and having a cam follower, a cam plate having a cam slot in which said cam follower rides, a chase aligning block secured to said chase block, aligning guides between which said chase aligning block passes to square the type when it presses against said platen, stop plates at the lower ends of said vertical guideways, and means for impressing vertical reciprocating motion on said chase block.

3. In a printing press, impression bar mechanism comprising first and second standards having vertical guideways, sliding blocks in said guideways, a chase block between said standards having parts journaled in said sliding blocks, a chase turning block outside of said first standard and connected to said chase block and having a cam roller mounted thereon, a cam plate outside said chase turning block and having a cam slot in which said cam roller rides, said second standard having a chase aligning block on the outer side thereof, said second standard having at its lower end a pair of aligning guides between which said chase aligning block passes to square the type, both said standards having stop plates at the lower ends of said vertical guideways, a pair of operating rods inside said standards connected to said chase block, and means for impressing vertical reciprocating motions on said operating rods.

4. In a printing press, an impression making device comprising an impression head, a platen, means for engaging said impression head and platen for printing, means for moving said im-

pression head to an easily inspectable position, an inking cylinder, a transfer roll, and means for moving said transfer roll from said inking cylinder to said impression head when the latter is in its upper position.

5. In a printing head, a frame, an ink-carrying roll, a horizontal platen, an impression bar carrying type, means for imparting a combined vertical and rotative movement to said impression bar so that, when in its upper position, the type faces the front of the machine and, when in its lower position, the type faces said platen, said impression bar carrying side rails, transfer mechanism comprising a pair of transfer arms pivoted to the 10 top of the frame, said transfer arms overlapping said side rails, said frame having vertical guideways, a pair of vertical guide bars in said guideways, a set of frames independently pivoted to said guide bars, each frame carrying a transfer 15 roll, said transfer rolls having rollers riding on said side rails and transfer arms, a cam plate having a cam slot attached to said impression bar, a follower riding in said cam slot and attached to said transfer arms, means for moving said impression bar and said vertical guide bars in oppo- 20

site directions, said transfer rolls riding up on said transfer arms to contact said ink cylinder and riding down on said side rails to apply ink to the type.

6. In a printing head, a frame, an ink-carrying roll, a horizontal platen, an impression bar carrying type, means for imparting a combined vertical and rotative movement to said impression bar so that, when in its upper position, the type faces the front of the machine and, when in its lower position, the type faces said platen, transfer mechanism comprising a transfer member engaging said impression bar, a vertical cross head, a frame pivoted to said cross head, said frame carrying a transfer roll, said transfer roll riding on 15 said impression bar and on said transfer member, a cam plate attached to said impression bar, a follower riding on said cam plate and attached to said transfer member, and means for moving said impression bar and said vertical cross head 20 in opposite directions, said transfer roll riding up on said transfer arms to contact said ink cylinder and riding down on said impression bar to apply ink to the type face.
